VACUUM PUMP

Application filed May 30, 1930. Serial No. 457,632.

This invention relates to vacuum blowers of centrifugal type such as adapted for service in connection with carrier systems and the like.

5 While the effect of blower operation in such service is to evacuate a part of the system so as to produce therein pressures below that of the atmosphere, of course the blower itself acts merely as a pump to move air from the system into the atmosphere. In other words, the rotor of the blower operates as always, except that its inlet is at a pressure below atmospheric. Since the air discharged by the rotor has already served its purpose, 10 its disposition is immaterial to the system, except where, as is often the case, the blower is so located indoors that drafts must be avoided.

It is the object of our invention to provide 20 simple yet efficient means for dissipating the rotor discharge with minimum agitation of the surrounding atmosphere, and to this end it is a further object of the invention to so proportion the rotor itself and associated 25 parts that the rotor discharge velocity is minimized without reducing the efficiency of evacuation.

The exact nature of the invention together 30 with further objects and advantages thereof will be apparent from the following description taken in connection with the accompanying drawings, in which Fig. 1 is a typical section on a diametral plane, of a blower constructed according to the principles of our 35 invention; and Fig. 2 is a detail of the same in end elevation and at a smaller scale.

With reference now to the drawings, 1 is the rotor, mounted on the shaft 2 carried in suitable bearings not shown, and arranged to 40 be driven by the usual electric motor or equivalent means. The rotor may be made up as indicated of a pair of spaced end disks 3 each secured with a hub casting 4 which in turn is secured upon a bushing 5 made fast 45 upon the shaft 2, by means of a nut 6.

Each of the rotor disks 3 is dished inwardly so that the space between the disks, longitudinally of the rotor, increases with the radial distance from the shaft 2. In other 50 words the so-called disks are actually cones.

Between the disks 3 are arranged in circumferentially spaced relation a number of radially extending blades 7. The hub 4 has an annular opening 8 opposite the end of the shaft 2, which serves as inlet mouth for the 55 rotor.

It will be apparent that the described divergence of the disks 3 toward the periphery of the rotor will provide a lower discharge velocity than would be the case were the disks 60 not dished as described.

A casing is provided for said rotor and may be constructed as indicated having a pair of castings 9, 10, serving as base portions. The casting 9 is annular and carried by the 65 neck 11 which as will be noticed has its through opening 12 diverging toward the mouth 8 of the rotor, the casting 9 fitting between these parts as indicated to provide a substantially uninterrupted passageway. 70 The casting 10 may be solid except for a central clearance opening 13 for the shaft 2. Secured respectively with the castings 9 and 10 are a pair of casing members 14 and 15 arranged one on either side, or more strictly on 75 either end of the rotor 1. These casing members 14 and 15 extend radially beyond the circumferential extremity of the rotor, and at their peripheries are connected by a cylindrical casing member 16 concentric with the 80 rotor. The members 14 and 15 may be stiffened by annular members 22 of angular section and with flanges inwardly turned immediately adjacent the rotor periphery. Thus an annular chamber 17 is formed, extending 85 about the periphery of the rotor to receive the discharge therefrom.

The casing parts which form this chamber 90 are also formed to provide controlled exit to the atmosphere for air forced into the chamber by the rotor. To this end the casing members 14 and 15 may be provided with a number of perforations 18 leading directly from the chamber 17. These perforations 95 preferably are formed by so punching their casing members as to leave outstanding necks 19 joined with their casing members by the curved annular shoulders indicated as at 20. Similar openings 21 may be provided in the peripheral casing member 16. 100

It will be apparent that by the described openings discharge from the chamber 17 will be quiet and with minimum agitation of the surrounding atmosphere, the casing providing an expansion chamber adapted to operate with the effect of a muffler.

What we claim is:

1. In a vacuum blower of centrifugal type, a rotor casing having a portion arranged peripherally of the rotor and perforated for dissipating the rotor discharge, and having at each perforation an outstanding neck portion supported by a curved shoulder portion, whereby discharge to the atmosphere will be with minimum agitation.
2. In a device of the class described, a blower rotor having diverging side walls to diminish acceleration of flow therebetween, a housing about said rotor and having an outer peripheral wall portion and side wall portions but being open inwardly to provide an annular trough-like receiver into which the rotor may directly discharge, said housing having its side walls extending radially inwardly of said receiver to enclose the side walls of the rotor, said receiver having perforations to allow discharge to the atmosphere.

In testimony whereof we hereby affix our signatures.

GEORGE R. BROWN.
GEORGE F. NAAB.
